CLAIM

The ornamental design for a linear guideway, as shown and described.

DESCRIPTION

FIG. 1 is a front elevational view of a linear guideway showing my new design;

FIG. 2 is a top plan view thereof;

FIG. 3 is a bottom plan view thereof;

FIG. 4 is a left side elevational view thereof; a right side elevational view is a mirror image of the left side elevational view;

FIG. 5 is a left, front, top perspective view thereof;

FIG. 6 is a top, front, left perspective view thereof; and,

FIG. 7 is a rear, top, left perspective view thereof.

1 Claim, 2 Drawing Sheets
